ABSTRACT: A mesh cathode comprising a tubular mesh grid formed of electron-emitting wires; the tubular grid having one end portion thereof fastened to an annular heating current supply terminal and having the other end portion thereof attached to a cap which is supported on a rod disposed coaxially of the tubular grid. The rod and the cap cooperate to form a second heating current supply terminal. The cap comprises a plurality of laminar members each having a plurality of arms extending radially outwardly from a centrally disposed hub having an aperture therethrough for fittingly engaging the supporting rod. The laminar members are arranged with the arms in a staggered pattern relative to each other.

MESH CATHODE FOR ELECTRON TUBES

BACKGROUND OF THE INVENTION

1. Field of the Invention

This invention relates to mesh cathodes for electron tubes of high capacity, and more particularly refers to transmitter tubes wherein the mesh cathode comprises a tubular mesh grid formed of electron-emitting wires having one end portion thereof fastened to an annular heating current terminal and having the other end portion thereof attached to a cap which is supported on a rod disposed coaxially of the tubular grid.

2. Description of the Prior Art

Mesh cathodes having a tubular mesh grid formed of electron-emitting wires have been proposed heretofore, and these prior art devices have been formed with one end portion of the tubular mesh grid attached to an annular heating current supply terminal and with the other end portion thereof attached to an elastic holding means for longitudinally tensioning the tubular grid to give the same an inherent stability without additional struts or supporting members. These prior art devices had one end portion of the tubular mesh grid attached to the elastic member to compensate for the heat expansion of the grid which occurred during the operation of the cathode. Such a prior art device is disclosed in German Pat. No. 839,225.

Furthermore, British Pat. 987,461 discloses one embodiment of an elastic-holding member for a mesh cathode, and in particular the mesh cathode disclosed therein includes an elastic cap secured to a support bar extending coaxially of the mesh cathode and forming one of the two heating current supply terminals of the cathode. In this particular prior art device, the cap is generally formed with a spiderlike configuration, and in particular includes an annular disc fastened to the central support rod and interconnected by means of a plurality of radially extending arms to a ring which seals the upper end portion of the tubular mesh cathode. The legs of this elastic member are first pulled downwardly and then bent upwardly at their terminal end portions.

Mesh cathodes of the type described hereinabove and including an elastic support member have the inherent problem of balancing the required elasticity with the required electrical conductive properties to transmit sufficient heating current from the central support bar to the tubular mesh grid. To provide adequate elasticity, the radially extending arms of the spiderlike support member are necessarily made as thin as possible. It should be understood, that the small cross section of the legs resulting from the elasticity requirement leads to an impractically high electrical resistance to the heating current supply. None of the mesh cathodes proposed heretofore have included an elastic support member having both adequate elasticity and sufficiently low electrical resistance.

To overcome the problem mentioned hereinabove, some prior mesh cathodes have been formed with a substantially inelastic cap member having sufficient electrical resistance properties and with the tubular mesh grid portion having a certain amount of elasticity. To provide the tubular mesh grid with elasticity, it has been proposed to weld only part of the intersecting points of the electron-emitting wires. However, welding together only part of the intersecting points of the electron-emitting wires adversely affects the stability of the tubular mesh grid, and therefore adversely affects the life expectancy of the mesh cathode.

SUMMARY OF THE INVENTION

A mesh cathode, constructed in accordance with the present invention, includes a tubular mesh grid formed of intersecting, electron-emitting wires with one end portion of the tubular grid fastened to an annular heating current supply terminal and with the other end portion thereof attached to an elastic cap member supported by a rod disposed coaxially of the tubular mesh grid. The rod and the cap cooperate to form the second heating current supply terminal. Also, the cap comprises a plurality of laminar members each member hav-

ing a plurality of arms extending radially outwardly from a centrally disposed hub which has an aperture therethrough for fittingly engaging the support rod. The laminar members are arranged in a staggered pattern relative to each other. Furthermore the terminal end portion of each radially outwardly extending arm is substantially bent upwardly to provide a particylindrical surface for engaging a ring member which interconnects the several arms of the laminar members thereby to hold the same in an assembled relationship. Desirably, the laminar members are not in direct face to face contact, but instead are separated by a foraminous member.

In this manner, a cap member for a mesh cathode is provided which has both the required electrical conductivity to supply the grid with sufficient heating current and the required elasticity to protect the tubular mesh guard against extreme deformations which occur during the operation of the cathode. A cap portion formed in accordance with the present invention presents a relatively large cross section to provide the necessary low electrical resistance while also permitting the laminar members to be kept as thin as is practical to provide the desired elasticity. The elasticity of the cap member is increased by interposing foraminous discs between the individual laminar member.

25 Thus, the present invention provides an elastic cap member having all the necessary requirements to permit the use of a tubular mesh grid having the electron-emitting wires mechanically interconnected at all the points of intersection. Although, the present invention is preferably utilized with a tubular mesh grid having each intersecting point mechanically interconnected, it should be understood, that the cap of the present invention may be utilized with a mesh grid having only part of its intersecting points mechanically interconnected.

30 Therefore, it is the primary object of this invention to provide a mesh cathode including a tubular mesh grid having one end portion thereof attached to an annular heating current supply terminal and having the other end portion thereof attached to an elastic cap member supported on a rod disposed coaxially of the tubular mesh grid, wherein the elastic cap member provides both the required elasticity and the required low electrical resistance to supply a sufficient heating current to the grid.

BRIEF DESCRIPTION OF THE DRAWINGS

In the accompanying drawings, forming a part of this specification and in which like reference characters are employed to designate like parts throughout the same;

FIG. 1 is a longitudinal sectional view of a mesh cathode embodying the features of the present invention;

FIG. 2 is a schematic view illustrating the material from which the tubular mesh grid of the present invention is formed;

FIG. 3 is a top plan view of the cap member of the present invention;

FIG. 4 is an enlarged sectional view of the cap member illustrating the portion enclosed within the circle designated as IV in FIG. 1;

FIG. 5 is a top plan view of one of the laminar members which form the cap illustrated in FIG. 3;

FIG. 6 is a plan view of one of the foraminous spacer member;

FIG. 7 is a top plan view of a special laminar member utilized to fill in the residual angular area left by the staggered relationship of the other laminar members; and

FIG. 8 is a sectional view of an arm portion of a cap member illustrating an alternative configuration and taken on a line as indicated by line VIII—VIII of FIG. 5.

DESCRIPTION OF THE PREFERRED EMBODIMENTS

Referring to the drawings, there is shown a tubular mesh grid 1 formed of a plurality of electron-emitting wires arranged in clockwise and counterclockwise spiral lines. As best illustrated in FIG. 2, the clockwise and counterclockwise

spiraled wires intersect as at 2 and have each point of intersection welded together

The tubular mesh grid 1 has one end portion thereof fastened to an annular heating current supply terminal 3 and has the other end portion thereof attached to an elastic cap member 4 which in turn is supported by means of a rod 5 extending coaxially of the tubular mesh grid. The elastic cap 4 and the rod 5 cooperate to form a second heating current supply terminal for the cathode. The elastic cap 4 further includes a centrally disposed aperture 13 having a diameter to permit fitting engagement with a reduced diameter portion as at 14 on the upper terminal end portion of the rod 5. The rod 5 has a shoulder 15 for supporting the cap 4 and further includes an externally threaded portion on the reduced diameter portion 14 for receiving a nut 16. The cap 4 is positioned between the nut 16 and the shoulder 15 with the nut 16 retaining the cap 4 and the rod 5 in an assembled relationship to provide an efficient electrical connection therebetween.

As best seen in FIG. 4, the elastic cap member 4 is composed of four identical laminar members 6 and one dissimilar laminar member 10. The four identical laminar members 6 are each formed with a hub portion 19 and nine arm portions 7 extending radially outwardly from the hub portion. The dissimilar laminar member 10 also includes a hub portion 21, but includes only one radially outwardly extending arm portion 7'. Each laminar member 6 and 10 is formed of a very thin sheet of conductive metal, for example tantalum or molybdenum. The four identical laminar members 6 and the one dissimilar member 10 are superposed one on the other and are desirably separated from adjacent laminar members by a disc 8 which is centrally disposed relative to the laminar members and which includes an aperture 22 coincidental with the apertures 13 of the laminar members. The interposed discs 8 permit the arm members 7 and 7', respectively of the laminar members 6 and 10, to flex independent of adjacent arm members. As illustrated in FIG. 3, the laminar members 6 and 10 are arranged with each radially outwardly extending arm portion 7 or 7', staggered relative to the other arm portions.

Also, each arm member 7 or 7' has its outermost end portion bent substantially upwardly to provide a particylindrical surface as at 23. Preferably, each arm portion 7 or 7' is of an identical width, and also is of a width such that the peripheral, particylindrical portion 23 of each arm portion is slightly spaced from, but not overlapping, its adjacent arm portions. Thus, the cap member 4 is formed with a plurality of circumferentially spaced particylindrical surfaces such as 23. The particylindrical portion 23 of each arm portion 7 or 7' is welded or otherwise secured to an outer cylindrical surface formed on a retaining ring 9, thereby to interconnect the laminar members at their peripheral edge portions.

To uniformly distribute the longitudinal tensioning forces exerted by the elastic cap 4 upon the tubular mesh grid 1, it is desirable to provide an arm portion 7 or 7' for each point of intersection present on the tubular mesh grid at its upper peripheral edge portion. For example, the tubular mesh grid 1 illustrated in FIGS. 1 and 2 includes 37 cathode wires spiraled in a clockwise direction and an additional 37 wires spiralled in a counterclockwise direction to form the grid mesh, thereby to provide 37 intersection points distributed about the upper circumference of the tubular mesh grid. Therefore, the elastic cap member 4 includes 37 circumferentially spaced arm portions 7 or 7'. The 37 circumferentially spaced arm portions may be provided by any number and arrangement of laminar members, but the preferred example, as illustrated in the drawings, includes four identical laminar members 6 and one dissimilar laminar member 10, with the four identical laminar members each containing nine identical, circumferentially spaced arm portions 7 and with the dissimilar laminar member containing one arm portion 7', thereby to provide a total of 37 arm portions.

To obtain the correct spacing, each identical laminar member 6 has the configuration illustrated in FIG. 5. In particular, the radially extending arm portion 7a has its axis cir-

cumferentially spaced from the radially extending axis of the adjacent arm portion 7b by an angle designated as A. The angle A is determined by dividing 360° by the required number of arm portions, for example 37, and multiplying that result by the number of identical laminar members, for example four. For the embodiment illustrated, the angle A is approximately equal to 38°, 55 minutes. For the laminar member 6, as illustrated in FIG. 5, the radially extending axis of each arm portion 7 is angularly spaced from its clockwise, adjacent arm portion by an angle equal to angle A, with the exception of arm portion 7h relative to the arm portion 7a. The angular spacing between the axes of arm portions 7h and 7a is greater than angle A to include the residual angle resulting from the difference between 360° and 9 × 38°, 55 minutes.

In accordance with the principles of the present invention, the dissimilar laminar member 10 includes only one arm portion 7' to provide the remaining 37 arm portion for completing the cap member. The arm portion 7' of the dissimilar laminar member 10 is disposed relative to the arm portions 7 of the four identical laminar members 6 to "fill in" the accumulated residual angles of the identical laminar members, thereby to provide a cap 4 having 37 equiangularly spaced arm portions 7 and 7'.

With the cap member 4 constructed as described hereinabove, each individual intersection point around the upper peripheral edge of the tubular cathode grid 1 is individually welded to one of the arm portions 7 or 7'. In this manner, a mesh cathode is provided which has an elastic cap member that provides the required elasticity and furthermore provides the necessary low electrical resistance to transmit the required heating current to the tubular mesh grid.

The preferred embodiment of the invention, as described hereinabove, may be modified to provide an increased elasticity of the cap member 4 by forming the radially outwardly projecting arm portions with at least one particircular impression therein as illustrated in FIG. 8 and as indicated at 29. It should be understood that the arm portion 7d', as illustrated in FIG. 8, distinguishes from the arm portion 7d, as illustrated in FIGS. 1 to 5 only by the addition of the impressions or dimples 29, and primed reference characters are employed to designate similar parts. To assure uniform elasticity of the arm portions, each arm portion of a cap member 6', constructed in accordance with this alternative embodiment, should have an equal number of impressions or dimples such as 29. Furthermore, the impressions desirably are formed with an arcuate shape in plan view and are arranged about the circumference of a common circle having an axis coincident with the axis of the cap member 6'. The impressions 29 form a point about which the arm portions such as 7d' may bend, while not decreasing the cross-sectional area of the arm portion, such as would occur by scoring the arm portions. Thus, the impressions such as 29 increase the elasticity without decreasing the electrical resistance properties of the cap member.

It has been found to be particularly advantageous to form each arm portion with two impressions such as 29, one at the outer end of the arm portion and one at the inner end thereof, as illustrated to FIG. 8, however, one impression such as 29, for example, at the inner end of the portion, is effective to increase the elasticity of the arm portion.

The preferred embodiment, as described hereinabove, includes a tubular mesh cathode having each point of intersection mechanically interconnected, although it should be understood that the advantageous properties of a cap member constructed in accordance with this invention is also applicable to a tubular mesh cathode having only part of the intersecting points mechanically interconnected.

Although minor modifications may be suggested by those versed in the art, it should be understood that I wish to embody within the scope of the patent warranted hereon all such modifications as reasonably and properly come within the scope of my contribution to the art.

I claim:

1. A mesh cathode for electron tubes comprising:

a tubular mesh grid formed of electron-emitting wire;
a first heating current supply terminal having an annular configuration closing one end of said tubular mesh grid;
an elastic cap member closing the other end of said tubular mesh grid and including:
several thin sheet metal laminar members superposed upon each other;
each said laminar member formed with at least one radially outwardly extending arm portions, each said arm portion being disposed in staggered relationship to other ones of said arm portions; and
a support rod disposed coaxially of the tubular mesh grid and supporting said elastic cap member;
said support rod cooperating with said cap member to form a second heating current supply terminal.

2. A mesh cathode as defined in claim 1, further comprising: disc members interposed between adjacent ones of said laminar members for axially separating said laminar members.

3. A mesh cathode as defined in claims 1 and 2 further characterized by:
said tubular mesh grid formed with spirally wrapped, intersecting, electron-emitting wires providing a series of circumferentially spaced intersecting points around the upper peripheral edge of said tubular grid; and
said elastic cap member formed to provide one said arm portion for each said intersecting point around the upper peripheral edge of said tubular grid.

4. A mesh cathode as defined in claim 3; further characterized by:
said electron-emitting wires forming said tubular mesh grid having all intersecting points thereof interwelded.

5. A mesh cathode as defined in claims 1, and 2 further characterized by:
each said arm portion having the outermost end portion thereof bent upwardly at right angles relative to the remainder of said arm portion to provide a generally axially extending peripheral portion; and

said arm portions being arranged to provide a plurality of circumferentially spaced peripheral portions around the circumference of said cap member.

6. A mesh cathode as defined in claims 1, and 2 further characterized by each said arm portion being formed with a particircular impression therein with said impressions formed on a circular line concentric with a longitudinally extending axis of said laminar members.

7. A mesh cathode as defined in claims 1, and 2 further characterized by said electron-emitting wires forming said tubular mesh grid being spirally wrapped with all points of intersection being interwelded.

8. In a mesh cathode for electron tubes comprising a tubular mesh grid formed of electron-emitting wire, a first heating current supply terminal closing one end of said tubular mesh grid, wherein the improvement comprises an elastic cap member closing the other end of said tubular mesh grid and comprising:
a plurality of thin sheet-metal laminar members superposed upon each other in laminar adjacency;
each said laminar member having at least one radially outwardly extending arm portion;
each said arm portion being disposed in circumferentially staggered relationship to other ones of said arm portions;
each said arm portion having an outer free end circumferentially spaced from free ends formed on said other arm portions;
means interconnecting said free ends of said arm portions with the other end of said tubular mesh grid;
support means disposed coaxially of the tubular mesh grid and supporting said elastic member; and
said support means cooperating with said laminar members to form a second heating current supply terminal.

9. A mesh cathode as defined in claim 8, further comprising disc members interposed between adjacent ones of said laminar members for axially separating said laminar members.
